(57) CLAIM

The ornamental design for a wall mount for bathrooms, as shown and described.

DESCRIPTION

FIG. 1 is perspective view of a wall mount for bathrooms showing my new design;

FIG. 2 is a front side elevation view thereof;

FIG. 3 is a top plan view thereof;

FIG. 4 is a bottom plan view thereof; and,

FIG. 5 is another perspective view of the wall mount for bathrooms, with the broken line showing of a towel hanging ring being provided for illustrative purposes only and forming no part of the claimed design.
